[57] **CLAIM**

The ornamental design for an optical data storage disc cartridge housing, as shown and described herein.

DESCRIPTION

FIG. 1 is a rear isometric view of an optical data storage disc cartridge housing according to the present invention; FIG. 2 is a top view of the cartridge shown in FIG. 1; FIG. 3 is a bottom view of the cartridge shown in FIG. 1; FIG. 4 is a rear view of the cartridge shown in FIG. 1; FIG. 5 is a front view of the cartridge shown in FIG. 1; FIG. 6 is a side view of the cartridge shown in FIG. 1; and, FIG. 7 is an opposite side view of the cartridge shown in FIG. 1.

Those portions of the cartridge shown in broken lines are included for illustrative purposes only and form no part of the claimed design.
